Primary Examiner — Susan Bennett Hattan*Assistant Examiner* — Omeed Agilee(74) *Attorney, Agent, or Firm* — Quickpatents, LLC; Kevin Prince(57) **CLAIM**

The ornamental design for a chemical caddy, as shown and described.

DESCRIPTION

FIG. 1 is a perspective view of a chemical caddy, showing my new design;

FIG. 2 is an alternate perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines showing a second chemical caddy in FIG. 1 and additional side-attached chemical containers in the figures depict environmental subject matter and form no part of the claimed design. The remaining broken lines depict portions of the chemical caddy that form no part of the claimed design. The dot dash dot broken lines depict the boundaries of the claim and form no part thereof.
